BROOM-SPREADING DEVICE

Murray P. Hendricks, Wheeling, W. Va.

Application October 19, 1938, Serial No. 235,833

1 Claim. (Cl. 15—168)

This invention relates to new and useful improvements in broom-spreading devices, and has for one of its objects the production of a simple and efficient means for spreading the straws of a broom to provide a maximum sweeping surface therefor.

A further object of this invention is the production of a simple and efficient broom bridle for supporting the straw spreading pins which pass through the broom straws for spreading the straws to provide a maximum sweeping surface, as the broom becomes worn.

Other objects and advantages of the present invention will appear throughout the following specification and claim.

In the drawing:

Figure 1 is a front elevational view of a broom showing my improved spreading device applied thereto;

20 Figure 2 is a side elevational view;

Figure 3 is an enlarged horizontal sectional view taken on line 3—3 of Figure 1;

25 Figure 4 is a fragmentary detail perspective view of a portion of the bridle and a portion of one of the spreading pins;

Figure 5 is a side elevational view of the bridle;

Figure 6 is a perspective view of one of the spreading pins.

By referring to the drawing it will be seen that 30 A designates the handle of the broom, and B the conventional head of the broom. In order to provide the proper spreading of the broom structure, which makes up the head B, I provide a plurality of pins 10, one type of which is illustrated in Figure 6, wherein each pin is provided with a tapered point 11 and a plurality of transverse apertures 12. These pins 10 are extended transversely through the broom head between the straws of the broom in the manner, as shown in Figure 1, 35 the pins 10 being placed just below the binding seams or stitchings. These pins 10 are arranged in proper spaced relation transversely across the head of the broom in the manner shown in Figure 1.

40 A triangularly shaped bridle 13 is supported upon each side of the broom head as shown in Figures 1 and 2, the apex 14 of each bridle extending upwardly to which is secured the lower end of a coil spring 15, the coil spring 15 in each 45 instance being anchored upon a suitable supporting pin 16 carried by the handle A. Each bridle 13 is provided with a horizontally extending safety pin shank 17, the pins 17 of the respective bridles extending through the apertures 12 of the 50 pins 10 upon opposite sides of the broom head, as

shown. The safety pin shank 17 has its free end 18 detachably engaging the hook 19 of the bridle 13. By means of this structure, it will be seen that the pins 10 will be detachably anchored in engagement with the bridle 13. The free end 18 5 may be notched, as at 18a, if desired, to provide an efficient retaining means.

As previously described, the pins 10 which constitute pegs, are forced between the straws of the broom head just below the binding seams for 10 the purpose of spreading the straws, and thereby making the sweeping surface of the broom sufficiently wide to cover a maximum surface. The springs 15 will permit the head to freely flex as 15 the broom is in operation and will also tend to pull the pins or pegs 10 upwardly toward the seams or stitchings C. When the broom-spreader is applied to the broom for service, the springs 15 must remain in stretched position in order to provide sufficient tension to exert a continuous 20 upward pull upon the pegs or pins 10. The pegs or pins 10 will, in this manner, be held in a tight position.

Each bridle 13 may be made of stiff wire bent in a triangular shape, as shown, the apex 14 being 25 engaged by the spring 15, as described. The latching hook 19 will provide an efficient means for holding the bridle in a closed position.

The two bridles 13 are applied to the broom head in opposite directions with respect to each 30 other, as shown in detail in Figure 3, the bridle on one side fastening at the left-hand side of the broom head, and the bridle on the other side fastening at the right-hand side of the broom head.

35 The broom-spreading device should not be applied to a new broom, but is adapted to be applied to a broom which has been worn or partly worn. As soon as the broom fails to give proper results in sweeping, the spreading device should 40 be applied. In actual practice, when applying the pegs or pins 10 to the broom one or two of the bottom binding seams or stitchings will be cut from the broom in order to make allowance for the pegs or pins and allow these pegs or pins to 45 be forced upwardly, as far as possible. The safety pin shank 17 may then be passed through the apertured ends of the pins, after the pins have been properly placed in position through the head of the broom as illustrated. As the broom continues to wear, further additional seams or stitchings may be cut and the pegs may be drawn upwardly to further spread the sweeping surface 50 of the broom.

55 It should be understood that certain detail

changes in the construction may be employed without departing from the spirit of the invention, so long as such changes fall within the scope of the appended claim.

5 Having described the invention, what I claim is:

A broom-spreading device comprising a pair of members forming a bridle, the members being adapted to fit upon opposite sides of the head of a broom, each bridle member being triangular in shape, spreading pins adapted to fit between the broom straws of the head of a broom, said pins

being apertured at the ends thereof, a safety pin shank carried by each bridle member and being threaded through the apertured ends of said pins for detachably holding the pins in engagement with the bridle members and being engaged by 5 another part of the member, springs engaging the members and adapted to be secured to a broom handle adjacent the head of the broom for providing a tension to draw the pins toward the handle of the broom and to permit the broom 10 head to freely flex.

MURRAY P. HENDRICKS.
